UNITED STATES PATENT OFFICE.

MORRIS S. WRIGHT, OF WORCESTER, MASSACHUSETTS.

PNEUMATIC ACTION FOR MUSICAL INSTRUMENTS.

1,057,474.

Specification of Letters Patent. Patented Apr. 1, 1913.

Application filed July 8, 1902. Serial No. 114,724.

To all whom it may concern:

Be it known that I, MORRIS S. WRIGHT, a citizen of the United States, residing at Worcester, in the county of Worcester and 5 Commonwealth of Massachusetts, have invented a new and useful Improvement in Pneumatic Actions for Musical Instruments, of which the following is a specification, accompanied by drawings forming a part of 10 the same, in which—

Figure 1 represents a pneumatic-action for a musical instrument embodying my invention and shown in vertical, sectional view through the center of the actuating 15 pneumatic valve. Fig. 2 is a plan view of so much of the pneumatic-action as embodies the pneumatic valves. Fig. 3 is a rear elevation of that portion of the pneumatic-action shown in plan view in Fig. 2. Fig. 4 represents a central, vertical, sectional view of the primary pneumatic or air controlling valve on a larger scale than that 20 shown in Fig. 1, and Fig. 5 is a central, vertical, sectional view of the primary pneumatic or air controlling valve showing 25 modifications in its construction.

Similar reference letters and figures refer to similar parts in the different views.

My invention relates to that class of pneumatic-actuating mechanisms for operating key-strikers or fingers for depressing the keys of a musical instrument, said pneumatic-actuating mechanisms being controlled by a moving strip of perforated 30 paper; and my invention consists in the construction and arrangement of parts as hereinafter described and pointed out in the annexed claims, whereby the mechanism is simplified and by which the several parts 35 of the mechanism can be constructed entirely or in part of metal, thereby increasing the durability of the structure and facilitating the construction and repairing of the 40 mechanism.

Referring to the accompanying drawings, 45 1 denotes a portion of the inclosing case or framework; 2 and 3 denote rolls for carrying a strip of perforated paper 4. The rolls 2 and 3 are provided with actuating 50 mechanism, not shown, by which the rolls are rotated and the paper moved over the

edge 5 of a tracker board 6. The edge of the tracker board is provided with a series of openings one of which is shown at 7, which are alternately opened and closed by 55 the movement of the perforated paper in the usual manner in instruments of this class. The opening 7 communicates with an air chamber 10 inclosed in a cup-shaped sheet metal shell 11. The upper edge 12 60 of the sheet metal shell 11 is adapted to receive the downwardly turned edge 13 of a flange 14 projecting from the lower end of a cylindrical valve body 15; and pinched between the downwardly turned edge 13 65 and the upper edge 12 of the shell 11 is the edge of a flexible diaphragm 16 upon which is mounted a valve stem 17 capable of a vertically sliding motion in the metal guides 18 and 19 as the diaphragm 16 is 70 raised or lowered by the variation of the air pressure above and below the same as hereinafter described. The diaphragm 16, with its inclosing metallic shell constitutes what I term the valve pneumatic, as it 75 serves to actuate the valve stem 17, and open and close the valves carried thereon. The cylindrical valve body 15 is divided horizontally by a metal partition 20 into two sections or chambers 21 and 22 which 80 communicate by an opening 23 in the partition 20. The upper end of the valve body 15 has an interior flange 24 provided with a central opening 25, forming a communication between the chamber 22 and the open 85 air. The metal partition 20 is preferably curved upwardly to form a bearing surface or valve seat 26 and the flange 24 is preferably curved downwardly to form a bearing surface or valve seat 25. The valve 90 stem 17 carries an upper valve 28 arranged to close the opening 25 when the valve stem is raised and a lower valve 29 arranged to close the opening 23 when the valve stem is depressed. The exterior surface of the 95 cylindrical valve body 15 is provided with a screw thread 30 by which it is inserted through screw threaded openings 31, 31 in a sheet metal box 32 which incloses a vacuum chamber 33 connected by a pipe 34 to 100 a bellows 35, of the usual form of construction in instruments of this class, by which

the air is exhausted from the vacuum chamber 33 and likewise from the chamber 21 by means of the openings 36 in the valve body 15. Screwed upon the upper end of 5 the valve body 15 is a sheet metal box 37 inclosing an air chamber 38 communicating with the upper valve chamber 22 by means of openings 39 forming a conduit to an inverted cup-shaped shell 40. The metal 10 box 37 is placed above and transversely to the metal box 32 and is screwed to the valve body 15 near one of its ends. Near the opposite end of the box 37 and attached to its under surface is an inverted cup-shaped 15 sheet metal shell 40 inclosing an air chamber 41 which communicates with the air chamber 38 by means of an opening 42. The lower open end of the cup-shaped shell 40 is closed by a flexible diaphragm 43 attached at its edge, in any suitable manner, to the edge of the cup-shaped shell 40, in the present instance by means of a metal 20 clamping ring 44. The flexible diaphragm 43 and its inclosing shell constitutes the motor 25 for pneumatic and serves to actuate the fingers or key striker as hereinafter described. Supported upon the flexible diaphragm 43 is a washer 45 which is connected by a link 46 with a lever 47 pivoted at one end to a 30 fixed stud 48 and connected at its opposite end by a link 49 with a finger or key-striker 50 pivoted about midway its length and provided at its opposite end with a cushioned head 52 which rests upon a key 53 of a piano 35 or other musical instrument.

An elastic gasket 54 is interposed between the sheet metal box 32 and the flange 14 of the valve body and a similar gasket 55 is interposed between the boxes 32 and 37; 40 said gaskets being compressed to form air tight joints.

In Fig. 5, I have shown a slightly modified form of construction which I consider preferable to that shown in Fig. 4, inasmuch as I do away with the necessity of forming a screw thread upon the entire length of the cylindrical valve body 15; and I effect the compression of both gaskets 54 and 55 by means of a short screw thread 56 45 on the upper end of the valve body 15 and a nut 57 provided with an interior flange 58 which forms the upper valve seat in lieu of the flange 24, Fig. 4, and with an exterior flange which forms a bearing surface for 50 the gasket 55. The outer surface of the valve body 15 is left plain as at 60, Fig. 5, except at its central section a circumferential groove 61 may be formed, if desired, to receive the inner edge of the upper gasket 55. 55 In the construction shown in Fig. 5, the sheet metal boxes 32 and 37 and the gaskets 54 and 55 are clamped between the flange 14 of the valve body and the nut 57; and all 60 the joints may be closed by tightening the

nut 57. Mounted upon the overhanging end 65 of the sheet metal box 37 is a sheet metal box 62 made semispherical in its cross section for convenience of construction and inclosing an air chamber 63 communicating by a pipe 64 with the vacuum chamber 33. The pipe 9 70 also communicates with the chamber 63 through a contracted opening 65. In Figs. 4 and 5, the valve stem 17 and valves 28 and 29 are represented as midway between their upper and lower positions in order to disclose the openings 39 more clearly. The valve stem 17, however, is normally in its lowest position with the lower valve 29 resting upon the valve seat 26 and closing the opening 23 between the upper and lower 80 valve chambers 21 and 22, while the opening 25 is open between the upper valve chamber 22 and the air. In lieu of the bellows 35, operated by a foot treadle 35^a, as is common in instruments of this class, any suitable means may be employed for the purpose of exhausting air from the vacuum chamber 33.

What I claim as my invention and desire to secure by Letters Patent is:—

1. In a pneumatic action for musical instruments the combination of a box inclosing a vacuum chamber and having openings in its opposite walls, a metallic shell communicating with the vacuum chamber 95 through one of said openings, a flexible diaphragm held in said shell, a box inclosing an air chamber and having inlet and outlet openings in its opposite walls, means for attaching said boxes together with their 100 openings in alinement, a valve stem held concentrically with said openings and operatively connected with said flexible diaphragm and valves carried by said valve stem for closing the inlet and outlet openings of said air chamber, substantially as described.

2. In a pneumatic action for musical instruments the combination of a box inclosing a vacuum chamber and having openings 110 in its opposite walls, a metallic shell communicating with the vacuum chamber through one of said openings, a flexible diaphragm held in said metallic shell, a box inclosing an air chamber and having inlet 115 and outlet openings in its opposite walls, means for attaching said boxes together with their openings in alinement, a valve stem held concentrically with said openings and operatively connected with said flexible diaphragm, valves carried by said valve stem for closing the inlet and outlet openings of said air chamber, and a motor pneumatic communicating with said air chamber, substantially as described.

3. In a pneumatic action for musical instruments, the combination of a box inclosing a vacuum chamber, a motor pneumatic,

a valve controlled passage connecting said motor pneumatic with said vacuum chamber, an opening in one of the walls of said vacuum chamber, a cylindrical metallic body 5 detachably held in said opening and having a flange at one end, a metallic shell detachably held by said flange outside said vacuum chamber, a flexible diaphragm held in said shell, and a valve for controlling 10 said valve controlled air passage operatively connected with said flexible diaphragm, substantially as described.

4. In a pneumatic action for musical instruments, the combination of a vacuum 15 chamber having an opening in one of its walls, of a metallic shell outside said vacuum chamber, a cylindrical body extending from said shell and inserted in the opening of said vacuum chamber, a flexible diaphragm 20 inclosed in said shell, a valve stem operatively connected with said diaphragm, an inlet opening to said vacuum chamber, and a valve carried by said valve stem for closing said inlet opening, substantially as described.

5. In a pneumatic action for musical instruments, the combination with a box inclosing a vacuum chamber and having an opening in one of its walls, of a metallic shell, a metallic cylindrical body detachably held in said opening and having an exterior flange outside said box, a metallic shell held by said flange, a flexible diaphragm inclosed in said shell, a gasket interposed between the wall of said vacuum 35 chamber and said flange and means for drawing said flange against said gasket, substantially as described.

6. In a pneumatic action for musical instruments, the combination with a vacuum 40 chamber, of a valve mechanism detachably attached to said vacuum chamber and comprising a valve body having an opening at one end forming a passage for the outside air, a shell inclosing an air chamber at the 45 opposite end of said valve body, a flexible diaphragm inclosed in said shell, a transverse partition dividing said valve body into two sections and provided with an air passage connecting said sections, a valve stem held 50 concentrically in said valve body and operatively connected with said flexible diaphragm, and a pair of valves carried by said valve stem and arranged to close said air passages, substantially as described.

55 7. In a pneumatic action for musical instruments, a detachable valve mechanism consisting of a valve body divided by a transverse partition into two sections, said partition having an opening forming an air 60 passage between said sections, an opening at one end of said valve body forming a passage for outside air, a shell at the opposite end of said valve body portion, a flexible diaphragm inclosed in said shell, an inlet

for air beneath said diaphragm, a valve stem 65 operatively connected with said diaphragm and valves carried by said valve stem and arranged to close said air passages, substantially as described.

8. In a pneumatic action for musical instruments, a valve mechanism consisting of a cylindrical valve body having an opening at one end forming a passage for outside air, a transverse partition dividing said valve body into two sections and having an opening forming an air passage between said sections, a screw thread at one end of said valve body, a nut carried by said screw thread, an exterior flange at the opposite end of said valve body, a cup shaped shell 80 held by said flange; a flexible diaphragm pinched between said cup shaped section and the edge of said flange, a valve stem operatively connected with said diaphragm and valves carried by said valve stem and 85 arranged to close said air passages, substantially as described.

9. In a pneumatic action for musical instruments the combination of a box inclosing a vacuum chamber, a box inclosing an air chamber, a screw threaded valve body inserted through said boxes and having openings communicating with each of said chambers, a valve controlled opening to the outside air at one end of said valve body, 90 a partition in said valve body having a valve controlled opening therethrough, a flange at the opposite end of said valve body, a shell supported by said flange, a flexible diaphragm in said shell, a gasket between said vacuum chamber box and said flange, a nut on the screw threaded valve body by which said gasket is compressed, and a valve stem and valves inclosed in said valve body, substantially as described. 100

10. In a pneumatic action for musical instruments, the combination of a box inclosing a vacuum chamber, a box inclosing an air chamber and having a valve controlled passage communicating with said vacuum 110 chamber, of a motor pneumatic detachably attached to said air chamber box and communicating therewith, said motor pneumatic consisting of a cup shaped open metallic shell, a flexible diaphragm covering the larger and open end of said shell and having its outer side exposed to the pressure of outside air, and means for attaching said diaphragm to said shell, substantially as described. 115

11. In a pneumatic action for musical instruments, the combination of a vacuum chamber, an air chamber a valve controlled passage connecting said chambers, a motor pneumatic consisting of a cup shaped metallic cover having its larger end open, a flexible diaphragm closing the open end of said shell and presenting one side to the 125

- pressure of outside air, and means for detachably connecting said shell with said air chamber, substantially as described.
12. In a pneumatic action for musical instruments, the combination of a box inclosing a vacuum chamber, a box inclosing an air chamber and having a valve controlled passage communicating with said vacuum chamber, a motor pneumatic detachably attached to the under side of said air chamber box, and consisting of an inverted cup-shaped metallic shell, a flexible diaphragm closing the under side of said shell, a lever pivoted at one end to a fixed stud, a link connecting the opposite end of said lever with a key striker, a pivoted key striker, and a link connecting said lever midway its length with said flexible diaphragm, substantially as described.
13. In a pneumatic action for musical instruments, the combination of a box inclosing a vacuum chamber, a box inclosing an air chamber, said boxes having holes in alignment, an interposed gasket between said boxes, a valve body passing through said boxes and having a circumferential groove to receive the edge of said gasket, substantially as described.
14. In a pneumatic action for musical instruments, the combination of an integral metallic box 32 inclosing a vacuum chamber, a valve controlling pneumatic detachably attached to said box 32, an integral box 37 placed transversely to said box 32, a motor pneumatic communicating with said box 37, openings in said boxes and means for attaching said boxes together with their openings in alignment and a valve for controlling the passage through said openings, substantially as described.
15. In a pneumatic action for musical instruments, the combination with a vacuum chamber and air chamber, of a valve body extending through the two and in communication with each, substantially as described.
16. In a pneumatic action for musical instruments, the combination with a vacuum chamber and air chamber, of a valve body extending through the two and in communication with each and a pneumatic connected to an end of the valve body, substantially as described.
17. In a pneumatic action for musical instruments, the combination with a metallic integral box inclosing a vacuum chamber and an integral metallic box inclosing an air chamber, of a separate metallic valve body passing through and detachably uniting said boxes, substantially as described.
18. In a pneumatic action for musical instruments, the combination of an integral metallic box inclosing a vacuum chamber, an integral metallic box inclosing an air chamber, and a separate valve body passing through and detachably uniting said boxes and having openings communicating with each, substantially as described.
19. In a pneumatic action for musical instruments, the combination with a metallic box inclosing a vacuum chamber and a metallic box inclosing an air chamber, of a metallic valve body detachably connecting said boxes and in communication with each of said chambers, and a valve controlling pneumatic located at one end of said valve body, substantially as described.
20. In a pneumatic action for musical instruments, the combination with a vacuum chamber, of an air chamber placed transversely to said vacuum chamber and forming a conduit to a motor pneumatic, a valve body extending through said chambers, and in communication with each a valve inclosed in said valve chamber, and a valve actuating pneumatic at one end of said valve body, substantially as described.
21. In a pneumatic action for musical instruments, the combination of an integral metallic box 32 inclosing a vacuum chamber, an integral metallic box 37 inclosing an air chamber, one of said boxes being placed above the other box and having openings in alignment, a metallic valve body passing through said openings and in communication with said vacuum and said valve chambers, substantially as described.
22. The combination with a metallic box inclosing a vacuum chamber and a metallic box inclosing an air chamber, of a metallic valve body connecting said boxes, a valve controlling pneumatic supported by said valve body, a valve stem controlled by said pneumatic, valves thereon and valve seats supported by the valve body and arranged to be engaged by said valves, substantially as described.
23. The combination with a vacuum chamber, an air chamber and a valve body extending through said chambers and provided with openings thereinto, of a pneumatic secured to one end of the valve body, a diaphragm therein, a valve stem operated by the diaphragm, valves carried by the stem and valve seats connected with the valve body, substantially as described.
24. The combination with two chambers having aligned holes, of a valve body fitting the holes, said valve body enlarged at one end and threaded at the opposite end, a nut screwed thereon, said nut having a valve seat, a seat within the body and a pair of valves adapted to engage said seats alternately, substantially as described.
25. The combination with two chambers having aligned holes, of a metallic valve body fitting the holes, said valve body enlarged at one end and threaded at the opposite end, a

nut screwed thereon, said nut having a valve seat, a seat within the body and a pair of valves adapted to engage said seats alternately and a pneumatic for operating the valves, substantially as described.

26. The combination with an integral metallic box inclosing a vacuum chamber, and an integral metallic box inclosing an air chamber, said boxes being superimposed one upon the other and having holes in alignment, of a separable valve body extending through said holes and detachably uniting said boxes, and a motor pneumatic detachably attached to said air chamber box, substantially as described.

27. The combination of a metallic box inclosing a vacuum chamber, a metallic box inclosing an air chamber at right angles thereto, a valve body connecting said boxes and communicating with said chambers and also with the outer air, a valve inclosed in said valve body for closing the opening to the outer air, a valve inclosed in said valve body for closing the passages between said boxes, a pneumatic at one end of said valve body operatively connecting with said valves and the motor pneumatic communicating with said air chamber, substantially as described.

30 28. The combination with a vacuum chamber, an air chamber, valve body and valves operating therein, of a primary pneumatic, a tracker board, a pipe leading therefrom to the pneumatic, said pipe having a vent, an air chamber into which the vent discharges, and a pipe leading from the air chamber to the vacuum chamber, substantially as described.

29. The combination with a vacuum chamber, an air chamber valve body and valves operating therein, of a primary pneumatic, a tracker board, a pipe leading therefrom to the pneumatic, said pipe having a vent, an air chamber into which the vent discharges, a pipe leading from the air chamber to the vacuum chamber, a main pneumatic connected with the outer end of the valve chamber, a lever and a striker operated by the diaphragm of said main pneumatic, substantially as described.

30 30. In a pneumatic action for musical instruments, the combination of a vertically disposed tubular valve body, a horizontally arranged box inclosing a vacuum chamber sleeved upon the wall of said valve body and communicating therewith, and a pneumatic element having a supporting part superimposed on the vacuum box and sleeved upon the wall of the valve body, the pneumatic element having communication with the valve body.

31. In a pneumatic action for musical instruments, the combination of a tubular

valve body, a vacuum chamber removably sleeved upon said valve body and communicating therewith, a pneumatic element having a supporting part also removably sleeved upon the valve body, the pneumatic element having communication with the valve body, and a single means for securing 65 said vacuum chamber and pneumatic in position, comprising a nut also sleeved upon the valve body and having interlocking engagement therewith.

32. In a pneumatic action, a tubular valve 75 body having an outward projection thereon, a vacuum box sleeved upon the valve body, a pneumatic element having a part sleeved upon the valve body and supported by the vacuum chamber, the vacuum box and pneumatic part being of independent construction and removable relative to one another, a nut threaded to the valve body for holding the pneumatic part and vacuum box in position, and a pneumatic element fitted to 80 the projection on the valve body, a valve actuated by said last mentioned element and a guide on the nut for the valve stem.

33. In a pneumatic action for musical instruments, the combination of a horizontally 90 extending vacuum chamber, a vertically arranged valve casing for communication with the vacuum chamber and said vacuum chamber and valve casing being supported one by the other, a motor pneumatic, and a 95 tubular member extending from the valve casing and constituting a support for the motor pneumatic.

34. In a pneumatic action for musical instruments, the combination of a horizontally 100 extending vacuum chamber, a vertically arranged valve casing having communication with the vacuum chamber and said vacuum chamber and valve casing being supported one upon the other and being independently 105 removable as complete units, a motor pneumatic, and a metallic tubular member forming a support for the motor pneumatic extending from the valve casing.

35. In a pneumatic action for musical instruments the combination of a horizontally 110 extending vacuum chamber, a vertically arranged valve casing having communication with the vacuum chamber and said vacuum chamber and valve casing being supported 115 one upon the other and being independently removable as complete units, a motor pneumatic, a support for the motor pneumatic extending from the valve casing, and said support being independent of the valve casing and independently removable.

36. In a pneumatic action for musical instruments, the combination with the vacuum chamber arranged horizontally of a valve casing arranged vertically and supported by 125 the vacuum chamber, a horizontally dis-

posed motor pneumatic spaced from the valve chamber and a support for the motor pneumatic extending from the valve casing.

37. In a pneumatic action for musical instruments, the combination of a tubular valve body, a vacuum chamber removably sleeved upon said valve body and communicating therewith, a pneumatic element having a supporting part also removably 10 sleeved upon the valve body, the pneumatic

element having communication with the valve body, and a single means for securing said vacuum chamber and pneumatic in position:

Dated this first day of July 1902.
